[57] CLAIM

The ornamental design of a tree stand for hunters, substantially as shown and described.

DESCRIPTION

FIG. 1 is a perspective view of a tree stand for hunters showing our new design;

FIG. 2 is a side elevation view thereof, the opposite side elevational view being a mirror image;

FIG. 3 is a top view thereof;

FIG. 4 is a front view thereof;

FIG. 5 is a bottom view thereof; and

FIG. 6 is a rear view thereof.
